BOLT TYPE EMERGENCY GOVERNOR

Filed Oct. 20, 1924

Inventor,
Frank C. Linn,
by *Frank C. Linn*
His Attorney.

UNITED STATES PATENT OFFICE.

FRANK C. LINN, OF LYNN, MASSACHUSETTS, ASSIGNOR TO GENERAL ELECTRIC COMPANY, A CORPORATION OF NEW YORK.

BOLT-TYPE EMERGENCY GOVERNOR.

Application filed October 20, 1924. Serial No. 744,700.

The present invention relates to emergency governors such as are used in connection with elastic fluid turbines, for example, to effect the closing of the emergency control valve means in case of excess speed. It relates especially to emergency governors of the bolt type wherein a bolt or plunger, the center of gravity of which is at one side of the center of the shaft, is held against movement normally by a spring but in case of excess speed is thrown out by centrifugal force and strikes a trip finger or trigger which, when moved, releases the emergency valve mechanism and permits it to close.

In connection with such governors, considerable difficulty has been experienced due to the bolt or plunger damaging or breaking the trip finger for, as will be appreciated, in the case of a shaft running at high speed, the head of the bolt or plunger strikes the trip finger with considerable force.

The object of the present invention is to provide an improved form of trip finger whereby the above referred to difficulty is overcome and for a consideration of what I believe to be novel and my invention, attention is directed to the accompanying description and the claims appended thereto.

In the drawing, Fig. 1 is a view, partly in section of an emergency governor mechanism embodying my invention, and Fig. 2 is a diagram.

Referring to the drawing, 1 indicates a shaft, for example, the shaft of an elastic fluid turbine. Mounted in a transverse opening 2 in the shaft is a bolt or plunger 3 the center of gravity of which is slightly above the center of the shaft, as viewed in Fig. 1. Bolt or plunger 3 is normally restrained from movement by a spring 4 which engages at one end a flange 5 on bolt 3 and at the other end a nut 6, which is adjustable on a sleeve 7 to vary the setting of the spring. Mounted adjacent the shaft in the plane of bolt 3 is a trip finger 8 which is pivoted at 9 and normally supports a rod 10, upon which a spring 11 presses. When the trip finger is turned in a clockwise direction, rod 10 is released and forced downward by spring 11. The movement of rod 10 effects the closing of the emergency valve. At 12 is indicated the resetting rod for trip finger 8. As viewed in the drawing, the shaft rotates in an anticlockwise direction.

The construction so far described is that

of a known type of emergency trip governing mechanism, the operation of which is well understood. The bolt 3 is thrown out by centrifugal force against the action of spring 4 in case of excess speed, striking trip finger 8 and turning it on its pivot 9 to release rod 10 and effect actuation of the emergency valve mechanism. In operating the bolt goes from its inner position to its outer position in a fraction of a revolution, as is well understood.

My invention relates especially to the construction of trip finger 8.

According to my invention I provide the trip finger with a striking face or actuating surface indicated at 13 which is concave and has a curvature such as to give substantially harmonic motion to the trip finger for equal angular motion of the head of bolt or plunger 3.

In laying out the curvature of the striking face 13, I may proceed as follows (see Fig. 2): With the point 14 as the center of rotation of the governor and with a radius proportional to the striking radius, I lay off an arc 15. Then with the same center and a radius proportional to the tripping radius plus a small amount to take care of variations in manufacture, I lay off a second arc 16. In this connection it is to be understood that by the striking radius I mean the distance from the center of rotation of the governor to the nearest point of the striking face of the trip finger which point is indicated at 17 in the drawing, and by the tripping radius I mean the distance from the center of rotation to the end of the plunger rod after it has been thrown outward to tripping position. The radial distance between arcs 15 and 16 represents the actual distance the trip finger is moved by the plunger. The length which the striking face is to have, that is the striking distance, has been selected and this distance on arcs 15 and 16 is divided into equal arcs by radial lines 18. Now with a point 19 on the arc 15 as a center and with a radius equal to the radial distance between arcs 15 and 16, an arc 20 is drawn from line 15 to line 16, and this arc is divided into a number of equal parts corresponding to the number of lines 18. Arcs from the center of rotation 14 of the governor are now drawn through the equidistant points on arc 20 to the corresponding radiating lines 18, thereby locating

points *a*, *b*, *c*, *d*, *e*, etc. which are points on the striking face of the trip finger. A line through these points then gives the contour for the striking face 13.

5 I have found in actual practice that by the use of a trip finger embodying my invention, difficulty due to the breaking of trip fingers is overcome. This is due to the fact that the improved trip finger when struck by the head of the bolt or plunger is set into motion and accelerated gradually and hence is not subjected to shocks as great as is otherwise the case. Also my improved construction enables the trip finger to be made lighter 10 in weight than heretofore and still possess the strength necessary to withstand the blows of the bolt or plunger. This is of advantage 15 in that it means that the inertia of the trip finger is less and that hence it is more easily set into motion.

In accordance with the provisions of the patent statutes I have described the principle

ple of operation of my invention, together with the apparatus which I now consider to represent the best embodiment thereof, but 25 I desire to have it understood that the apparatus shown is only illustrative and that the invention may be carried out by other means.

What I claim as new and desire to secure 30 by Letters Patent of the United States, is:—

In an emergency governor, the combination of a rotating striking member, and a trip finger having a striking surface adapted to be engaged by the rotating member, said 35 striking surface being concave and having a curvature such that the initial movement of the trip finger is comparatively small and successive equal angular movements of the striking member produce gradually increasing 40 outward movements of the trip finger.

In witness whereof, I have hereunto set my hand this 17th day of October, 1924.

FRANK C. LINN.
